STREET SWEEPER

Philip G. Patch, Pasadena, Calif. (% Patch & Kase Corporation, 3540 Wilshire Blvd., Los Angeles, Calif.)

Filed Oct. 14, 1959, Ser. No. 57,929

Term of patent 14 years

(Cl. D14—3)

Fig. 1 is a side elevational view of a street sweeper embodying my new design;

Fig. 2 is an elevated plan view;

Fig. 3 is a rear end view of the instant design;

Fig. 4 is a reduced view of the other side of my new street sweeper; and

Fig. 5 is a perspective view showing the front, top and one side of my new street sweeper design.

I claim:

The ornamental design for a street sweeper, as shown.
